INK FOUNTAIN

Henry A. Wise Wood, New York, N. Y., assignor to
 Wood Newspaper Machinery Corporation, New
 York, N. Y., a corporation of Virginia

Application August 4, 1932, Serial No. 627,438
 Renewed May 28, 1937

3 Claims. (CL 101—350)

This invention relates to ink fountains for printing presses and the like and particularly for presses printing in different colors.

The principal objects of the invention are to provide the fountain of the inking device in a plurality of units, individually removable; to provide an ink fountain of a length less than the full width of the paper to be printed, and to provide a fountain having separately removable containers for inks of different colors.

Other objects and advantages of the invention will appear hereinafter.

Reference is to be had to the accompanying drawings, in which

Fig. 1 is an end view of a part of a printing press showing a preferred embodiment of this invention, the fountain being shown in section;

Fig. 2 is a plan of a part of the ink fountain;

Fig. 3 is a side elevation;

Fig. 4 is a sectional view of a part of the fountain showing the adjusting device.

When different colored inks are used in the same inking system, it has been customary heretofore to have a single fountain with partitions in it separating it into compartments for the different color inks. This involves some difficulty owing to leakage through the partitions and especially to the fact that it is difficult to clean one of the compartments when it has to be emptied and a different colored ink put in it. This invention is designed to eliminate these difficulties and to avoid the delay and difficulty of the cleaning of the fountains.

The invention is shown as applied to an inking mechanism for a newspaper or the like having a fountain for each page width of the press, the fountain being shown as of the overshot type, although the invention is not limited to that type of fountain. Only the plate cylinder 2 of the printing couple is shown and it is illustrated as supplied with ink through a system of the ordinary type, which involves form rolls 3, ink drum 4, distributor 5, transfer roller 6, pick-up roller 7 and spray catcher 8. The fountain roll 9 runs very close to the pick-up roller 7 but does not touch it. These inking rollers are arranged as is usual in this art.

The combined fountain is made up of fountain roll sections 9, each one of approximately one page width, that is, sufficiently wide to ink a single page. Each fountain roll is rotatably supported in a small fountain bowl 10. Each one of these bowls constitutes a section of the main fountain in the same way that the short fountain roll does of the main fountain roll.

Each fountain roll is driven through a gear 11 secured to the end which projects through the fountain bowl. It meshes with a gear 12, carried on the shaft 13, which extends across the width of the press. The shaft 13 is driven from a source of power through bevel gears 14 and 15. Of course, there is one gear 12 for each movable fountain which cooperates with its corresponding gear 11 carried on the end of that particular fountain roll.

A brace 16 provides means for mounting each removable fountain bowl 10 which rests on a machined surface on its upper side. This machined surface cooperates with feet 17 on the several fountain bowls and the latter carry a T-slot construction fitting over T-bars 18. These T-bars are yieldingly pressed upwardly by springs 19 to provide a clearance so that the fountain bowl 10 may be slipped on and held in position. Adjusting lugs 21 are provided which threadedly carry adjusting screws 23. These screws 23 bear against bars 29 which may be considered as integral with the brace 16 and extend between feet 17. They are used for adjusting the fountain roll to the desired distance from the pick-up roll 7. Each individual fountain bowl of course is adjusted in a way to adjust the position of its fountain roll.

Each fountain bowl is fixed in adjusted position by a hinged bolt 28 secured to bar 29 and thumb nut 22 so that good inking can be obtained. Each fountain bowl 10 is securely clamped by lock bolts 20 to the brace 16 by the T-bars 18 against the underslung ledges of the fountain bowl.

In each fountain bowl is a fountain back 24 secured to provide a rigid mounting for the blade 25 by a clamping strip 26. The usual fountain blade adjusting screws 27 are provided and regulated in the usual manner.

The adjustments have been described and the method of fastening the parts in position. When it is desired to clean one of the fountain bowls 10, the bolts 20 are loosened, wing nuts 22 are loosened and bolts 28 swing down, permitting the entire bowl with its contents to be lifted free of the press without disturbing the other fountain bowls. The ink may be emptied and the fountain thoroughly cleaned in an efficient and easy manner and returned to position with equal facility.

Although I have illustrated and described only one form of the invention I am aware of the fact that modifications can be made therein by any person skilled in the art without departing from the scope of the invention as expressed in

the claims. Therefore I do not wish to be limited in this respect otherwise than as set forth in the claims, but what I claim is:—

- 5 1. In a printing press, the combination with a plate cylinder and a series of rolls for transferring ink thereto, of a plurality of fountain bowls arranged end to end, a fountain roll in each bowl for supplying ink to the ink rolls, said fountain roll being less than full page width of the press, and quickly detachable means projecting to an 10 accessible point in front of the bowl whereby each fountain bowl is independently detachable and removable.
- 15 2. In an inking device, the combination of a plurality of fountain bowls, each one of a width sufficient to supply ink for a single page of the printed product, a fountain roll therein of sub-

stantially the same width, a brace running under the several bowls, open slotted lugs carried by said bowls, jointed adjusting screws extending through the lugs and capable of being detached from them readily, and a bar integral 5 with the brace against which said screws bear whereby the bowl may be individually adjusted.

3. In an inking device, the combination of a plurality of separate ink bowls, a plurality of T-bars extending under said bowls, said bowls having feet in which T-slots are provided for receiving the T-bars, means for pressing said T-bars upwardly and yieldingly, and means for clamping the T-bars down in position to hold the bowls. 10
